UNITED STATES PATENT OFFICE.

PAUL ROCHE, OF ST. ETIENNE, FRANCE.

SPANNER OR NUT WRENCH.

Application filed March 5, 1924, Serial No. 697,078, and in France January 16, 1924.

The invention relates to nut wrenches or spanners, and according to the invention a displaceable slide and bolt allow sockets of different diameters to be used without changing the handle and without detracting from the proper functioning of the tool.

The accompanying drawing represents by way of example a spanner according to the invention:

10 Fig. 1 is an axial longitudinal section of the spanner provided with the displaceable slide and bolt.

Figs. 2 and 3 are respectively front and rear views of the spanner.

15 Fig. 4 is a section on the line 4—4 of Fig. 1.

The handle 1 is provided with an aperture 2 in which a rod 3 integral with the slide 4 can be shifted and secured as required 20 by a suitable nut 5. The slide 4 is guided laterally in a guide 6 integral with the handle 1; the faces of the guide may be plain as shown in Fig. 4, or dovetailed, or formed in any other suitable manner. At the end 25 of the slide 4 there is a bolt 7 of which the beveled part 8 can enter one of holes 9 of suitable form (round, oval, etc.) provided on the periphery of the socket 10. The socket is open at each end 11, the openings being of 30 rectangular hexagonal or other desired section and of different dimensions. Around the bolt 7 there is a spring 12, one end of which rests against a shoulder 13 of the slide 4. The spring constantly presses the bolt 7 forward, the bolt being retracted by means 35 of a milled head 14. When the socket 10 is to be replaced by another having a larger or smaller diameter, it is only necessary to move the slide 4 either upwards or downwards so that the bolt 7 is disengaged from

one of the holes 9 of the socket 10. The part of the socket containing the holes 9 has an external flange 15. This flange is provided to secure the socket 10 to the handle 1 by means of the slide 4.

45 The slide 4 and the corresponding part of the handle 1 are shown provided with notches 16 in order to fix the parts more securely together.

In order to use the spanner in the case 50 where the nut to be tightened or loosened is close to a wall or the like, the opening for the socket is disposed eccentrically in the head 17 of the spanner so that there is only a very small portion 18 at the head 55 of the spanner which might otherwise interfere with the use of the tool.

Having thus described the nature of the said invention and the best means I know of carrying the same into practical effect, I 60 claim:—

The combination with a handle provided in one end with a nut socket receiving opening, a slide mounted upon the handle adjacent said opening, the free end of the 65 slide being provided with a socket-engaging recess, means for locking the slide in adjusted position, and a spring projected socket engaging bolt mounted in and carried by the slide, of a socket insertible within 70 the opening of the handle and provided with an annular projection to fit the recess of the slide and be held against outward displacement relatively to the handle, and with openings to receive the bolt, the bolt and 75 openings cooperating to hold the socket against rotation.

In testimony whereof I have signed my name to this specification.

PAUL ROCHE. [L.S.]
